CLAIM

The ornamental design for an interlocking shelf bracket for a firewood rack or similar article, as shown and described.

DESCRIPTION

FIG. 1 is a left end, top and front view of an interlocking shelf bracket for a firewood rack or similar article showing our new design;

FIG. 2 is a front elevational view thereof;

FIG. 3 is a top plan view thereof;

FIG. 4 is a left end elevational view thereof; and

FIG. 5 is a bottom plan view thereof.

The right end and the rear of the bracket not shown are substantially the same as the views of the left end and front shown in FIGS. 4 and 2, respectively.
